UNITED STATES PATENT OFFICE.

JAMES ALEXANDER SERENE, OF KITTANNING, PENNSYLVANIA.

POLE-CLIMBER.

1,189,006.

Specification of Letters Patent. Patented June 27, 1916.

Application filed March 11, 1916. Serial No. 83,518.

To all whom it may concern:

Be it known that I, JAMES A. SERENE, a citizen of the United States, residing at Kittanning, in the county of Armstrong 5 and State of Pennsylvania, have invented certain new and useful Improvements in Pole-Climbers, of which the following is a specification, reference being had therein to the accompanying drawing.

10 My invention relates to improvements in pole climbers, the primary object of which is to devise such a climber having a removable gaff constructed to be surely locked in place without employing screws, bolts, rivets or welding as has previously been the manner in which removable gaffs have been attached.

Another object of the present improvement is to so construct the gaff and locking 20 means that the gaff may be readily and easily applied and locked and unlocked and removed without the use of special tools.

Other objects and advantages of the present improvement will be set forth in the following description and drawings, in which—

Figure 1 is an edge elevation of a pole climber constructed in accordance with my improvement. Fig. 2 is an enlarged fragmentary vertical sectional view of the body 30 portion of the climber and showing the gaff in position to be locked in place and also the position the gaff assumes when ready to be withdrawn. Fig. 3 is a view similar to Fig. 2, only showing the gaff locked in position in the shank of the climber. Fig. 4 is a fragmentary enlarged side elevation showing the slot in the shank of the climber in which the gaff is inserted. Fig. 5 is a front elevation of the gaff. Fig. 6 is a cross-sectional view taken on the line 6—6 of Fig. 2.

Referring now to the drawings in detail in which like reference numerals designate similar parts throughout the several figures, my improved climber comprises a shank 1, 45 which lies adjacent the leg of the wearer having at its upper end a loop 2, through which a strap (not shown) passes, which is buckled around the leg of the wearer in the usual manner in such devices. The shank 1 is bent inwardly at the point 3, the object of 50 which will be hereinafter set forth. The shank 1 is provided with the usual form of foot support 4 integral therewith, which foot support is provided with a loop 5,

through which a strap (not shown) is passed 55 and buckled to the foot of the wearer in the usual manner in such devices.

The outside lower portion of the shank 1, which is constructed of band metal is provided with a thickened portion 6 within the 60 center of which is formed a longitudinally tapered slot 7. This slot 7 is of dovetailed form having tapered inner walls 8. The upper end of the slot 7 is provided with an inwardly inclined portion 9, the upper end 65 of which is pierced with a hole 10, the purpose of which will be hereinafter set forth. A gaff 11 is provided having a sharp spike portion 12, to engage the pole or tree in climbing. The body portion of 70 the gaff is tapered at 13 to fit within the tapered slot 7. The taper of the slot 7 and gaff 11 are so arranged that there will be a tight fit between the two when the upper end of the gaff is near the end of the slot. 75 In assembling the parts the gaff 11 is first inserted in the slot 7 and pushed upwardly until a tight fit occurs between them and the gaff occupies the position shown in Fig. 2. The extreme upper end 14 of the gaff 80 11, which is relatively of thin cross-section, is then forced inwardly by means of a hammer or any other convenient means until the said end 14 lies directly against the inwardly inclined portion 9, of the 85 slot 7, as is shown in Fig. 3. This forcing of the end of the gaff inwardly securely locks it in place at all times and prevents it from being dislodged when strain is put upon it in withdrawing the gaff from the 90 wood in which it is forced when in operation. When it is desired to remove the gaff for the purpose of inserting a new one or sharpening it, a nail or other convenient means is inserted through the hole 10, from 95 the inside of the shank and then hit with a hammer or other device until the end 14 of the gaff is dislodged from the inclined portion 10, at which time the gaff may be freely withdrawn. It is to be understood that the 100 whole gaff is made of relatively malleable material and the same may be bent a number of times without breaking. Due to the fact that the shank 1 is curved inwardly at 3, the spike portion 12 of the gaff 11 is in 105 vertical alinement with the outer side of the loop 2, and when the leg of the wearer lies adjacent the pole no lever action will

take place to dislodge the gaff as would otherwise exist were the gaff not located as is shown and described.

From the above it is apparent that I have devised a removable gaff which is easily applied to a pole climber shank and held firmly in place during operation and yet which may be readily withdrawn when desired; the locking and unlocking of the gaff 10 requiring no special tools.

It will be observed that in this construction when the upper end 14 of the gaff is forced outward, that it serves as means whereby the gaff can be forced out of its 15 slot if it should be tightly wedged therein. Furthermore it is apparent that I have devised a removable gaff comprising only a gaff and slot and requiring no bolts, rivets, screws or welding for holding the same in 20 position.

Having thus described my invention, what I claim and desire to secure by Letters Patent is—

1. In a pole climber, the combination 25 with a shank provided with a vertically arranged slot on its outer side, the upper end of the slot deflected, of a gaff fitting within the slot with its upper end extending over and bent into the deflected portion of the 30 slot to lock the gaff therein.

2. In a pole climber, the combination with the shank thereof having a vertically arranged dove-tail shaped slot on its outer side having its upper end deflected in-

wardly, of a gaff with a dove-tailed portion 35 fitting within the slot, the upper end of the gaff extending over and forced into the deflected portion of the slot to form a lock.

3. In a pole climber, the combination with the shank thereof having a vertically arranged gaff receiving slot on its outer side, the upper end of the slot deflected inwardly, of a removable gaff fitting within the slot and having a relatively thin upper end located adjacent the deflected portion of the 45 slot and adapted to be bent inward for locking the gaff and forced outward for unlocking the gaff.

4. In a pole climber, the combination with the shank thereof having on its outer side a 50 vertically arranged gaff receiving slot, the upper end of the slot deflected inward, of a removable gaff fitting within the slot and having a relatively thin upper end adapted to be forced inward to the deflected portion of the slot to lock the gaff and to be forced outward to unlock the gaff, the shank having a transverse opening therethrough communicating with the deflected portion 55 of the slot for the insertion of a device to force the upper end of the gaff outward for unlocking it.

In testimony whereof I hereunto affix my signature in the presence of two witnesses.

JAMES ALEXANDER SERENE.
